CLAIM

The ornamental design for a chair design, as shown and described herein.

DESCRIPTION

FIG. 1 is a perspective view of a chair design according to an embodiment of the present invention.

FIG. 2 is a front view of a chair design according to an embodiment of the present invention.

FIG. 3 is a left side view of a chair design according to an embodiment of the present invention.

FIG. 4 is a back view of a chair design according to an embodiment of the present invention.

FIG. 5 is a top view of a chair design according to an embodiment of the present invention; and,

FIG. 6 is a bottom view of a chair design according to an embodiment of the present invention.

The broken lines shown in FIGS. 6 depict environmental subject matter only and form no part of the claimed design. The right side view is a mirror image of the left side shown in FIG. 3.
